UNITED STATES PATENT OFFICE

158,385

SHOE OR SIMILAR ARTICLE

Faie Joyce, Pasadena, Calif.

Application June 18, 1949, Serial No. 3,395

Term of patent 3½ years

(Cl. D7—7)

To all whom it may concern:

Be it known that I, Faie Joyce, a citizen of the United States, residing in Pasadena, in the county of Los Angeles, State of California, have invented a new, original, and ornamental Design for a Shoe or Similar Article, of which the following is a specification, reference being had to the accompanying drawing, forming a part thereof.

The essential features of my design are shown in full lines.

I claim:

The ornamental design for a shoe or similar article, substantially as shown and described.

FAIE JOYCE.
